 South Boston, Mass., a corporation of
 Massachusetts

Application July 14, 1931, Serial No. 550,651

5 Claims. (Cl. 173—328)

This invention relates to an electrical connection and particularly to a plug and socket connection.

In general, the invention has for an object to provide a plug and socket connection of novel and improved construction, which is particularly designed for use in high tension circuits with maximum safety and in which the plug and socket members are insulated from one another in a novel and superior manner.

With this general object in view and such others as may appear, the invention consists of the electrical connection, and in the various structures, arrangements and combinations of parts hereinafter described and particularly defined in the claims at the end of this specification.

In the drawing illustrating the preferred embodiment of the invention, Fig. 1 is a longitudinal sectional view of a high tension plug and socket connection embodying the features of the present invention; Fig. 2 is a cross-section on line 2—2 of Fig. 1; and Fig. 3 is a detail in section on line 3—3 of Fig. 2.

Referring to the drawing, which as above stated illustrates the preferred embodiment of the invention, as therein shown the electrical connection includes a plurality of plug members 10 adapted to be inserted into and withdrawn from cooperative socket members 12. The plug members 10 may be mounted within a metal casing 14 and the socket members 12 may be mounted within a similar casing 16, and as herein shown provision is made for detachably connecting together the casings 14, 16 to form a unitary structure when the plug members 10 are inserted into the socket members 12 in the use of the electrical connection. The casings 14, 16 may be provided with suitable openings 15 for the cables to be connected to the plugs and sockets and with a coupling 17 for detachably connecting the casings together. A key 19 cast within the casing 16 is adapted to fit into a groove in the casing 14 to insure that the proper plug cooperates with the proper socket.

The present construction of plug and socket unit is particularly designed for use in high tension circuits to provide a plug and socket connection in which the plug and socket members are insulated from each other in a novel manner designed to prevent breaking down of the insulation in the event of arcing, which affords maximum safety, and minimum liability of current leakage and/or flash over from one plug or socket member to another, and also from any

plug or socket member to the casing or to the ground.

As herein shown the plurality of plug members 10 are operatively supported in spaced relation within the plug casing 14 by a transverse insulating supporting member 20 of substantial thickness and herein shown as comprising a disk provided with a plurality of spaced holes therein through which the individual plug members 10 and tubular insulation 21 extend, as will be described. The insulating supporting disk may be secured to lugs 22 cast integrally with the casing 14 by a plurality of bolts 24, as illustrated. Each plug member is itself insulated within a tubular body of insulation 21 which is arranged to extend a substantial distance beyond one end of each of the plug members, and as herein shown each insulating tube 21 comprises an insulating tube 26 of substantial thickness, which is arranged to extend through one of the holes in the partition or supporting member 20 and is provided with a shoulder 28 which bears against one face 29 of the insulating supporting member 20. A threaded insulating sleeve 30 is screwed upon the externally threaded outer end portion of the insulating tube 26 and into engagement with the second surface 31 of the insulating supporting member 20 to thereby clamp to the support 20 the insulating tube 26 and the other insulating parts carried thereby and which make up the complete tubular insulation 21. Each plug member 10 is preferably provided with the usual socket 40 at its outer end into which the end of the cable may be soldered to connect the cable to the plug, and the socket end of the plug is enlarged to provide a shoulder 42. A tubular insulator 44 having a threaded portion 45 is screwed into the threaded outer end of the insulating tube 26, to thereby clamp the head of the plug 10 between it and the outer end of an elongated insulating tube 46, screwed into the second end of the insulating tube 26. It will be observed by reference to Fig. 1 that each plug 10 is clamped between the ends of the insulating tubes 44, 46, both of which are threaded into the insulating tube 26, and the latter is clamped to the transverse insulating support 20 so that the insulation for each plug, as well as the plug itself, is thus mounted upon and supported by the transverse insulating support 20, and the latter is mounted within the casing 14 to be movable as a unit therewith.

The holes within the transverse insulating supporting member 20 through which each plug and its insulation extend are spaced sufficiently so

as to provide a substantial air space between the insulation of adjacent plug members. The spacing of the plug members and their individual solid insulation from each other to surround each with a substantial body of air forms a desirable and efficient insulation comprising the solid insulation together with the interposed body of air. This method of insulating the individual plug members from each other has proven to provide 10 safe and highly efficient insulation when the connector is used in high tension circuits. Tests have demonstrated that even if the tubular insulation is punctured, should the connector be subjected to voltages many times in excess of its intended 15 capacity, very little insulating efficiency is lost since after the extinction of the arc, the air alone serves as adequate insulation.

The insulation for each plug member is extended a substantial distance beyond the outer end 20 of the plug, as clearly shown in Fig. 1, so that a relatively long path is interposed for reducing to a minimum current leakage, creepage, or flash over from the head of one plug to the other over the surface of the insulation, particularly when 25 the connection is subjected to humid conditions, and as illustrated, it will be observed that in order to travel from one plug to the other, it is necessary for the current to traverse the inner surface of the insulating tube 44 and thence down the outer surface of the insulating sleeve 30 and 30 across the intervening portion of the insulating support 20, and thence out the outer surface of an adjacent insulating tube 44 to the second plug, and this indirect relatively long path which is 35 interposed for the passage of the leakage of the current, together with the substantial air space between the heads of adjacent plugs, reduces to a minimum the chance for current leakage from one plug to the other to occur.

40 It will also be observed that each plug member 10 is itself enclosed within a relatively long tubular insulation extended a substantial distance beyond each end of the plug. As above stated each plug member 10 is adapted for insertion into a corresponding socket member 12 and each socket member 12 is mounted within a transverse insulating partition 60 in a manner similar to the manner in which the plug members are mounted in the transverse partition 20, as above described, 45 and as herein shown each socket member 12 is provided with an enlarged head 62 having a socket 63 into which the end of the cable may be inserted and soldered, and the head 62 of each socket member is clamped between an insulating piece 50 61 which is threaded and screwed into the interior of an elongated main insulating tube 64 and an insulating tube 66 which is also threaded and screwed into the outer end of the threaded hole in the outer end of the main insulating tube 64. 55 Each insulating tube 64 thus operatively supports the socket member 12 within it and the tube 64 is arranged to extend through a preformed hole in the transverse partition 60 and such holes are spaced apart, as illustrated, to provide a substantial air space between the insulating tubes 64. 60 Each tube 64 is clamped to the transverse partition 60 by an insulating clamping sleeve 67 screwed onto the end of each tube as shown. The insulating tubes 64 are of sufficient length to extend a substantial distance beyond each end of their socket members, thus reducing to a minimum the liability of current leakage and/or flash over from the head of one socket to the head of an adjacent socket in a manner similar to the 65 mounting of the plugs 10 within their insulation,

as above described. It will also be observed that the substantial air space interposed between adjacent insulated sockets provides a combined insulation, which, as in the case of the plug members, as above set forth, efficiently insulates the 5 sockets from one another and from the casing and enables the connection to be used in high tension circuits with maximum safety.

The socket insulating tubes 64 may and preferably will be of a size sufficient to telescope over 10 the ends of the plug insulating tubes 46 when the plugs 10 are inserted in the sockets 12, and the insulating tubes 64, 46 are preferably made of such length as to remain in telescoping relation during the operation of withdrawing the plugs 15 from their sockets and until the plugs have been separated from the sockets.

It is to be understood that in practice the present plug and socket connection will be broken 20 only after the power has been cut off by the usual means, such as the usual oil circuit breakers. Should, however, any minor arcs be formed when the ends of the plugs leave their sockets, the telescoping relation of insulation of the plug and 25 socket members affords additional protection.

The present construction of electrical connection is designed for use under all sorts of weather 30 conditions, and in practice the telescoping relation of the casings 14, 16 serves to render the connection weather-proof. In certain instances, 35 however, it may be desirable to render the connection water-tight, and for this purpose it is preferred to interpose a gasket 18 of rubber or other waterproof packing within the coupling 17. A rubber gasket 23 may and preferably will also 40 be provided at the end or ends of the casing through which the cable extends, it being understood that in certain instances a threaded coupling will be provided at one end of the casing when the electrical connection is to be screwed upon a conduit. In other instances the rubber gasket construction may be provided at both ends of the outer casing when the electrical connection is not intended to be screwed onto a conduit.

The heads of the individual plug and socket 45 members are preferably loosely supported within their individual insulation to permit sufficient play as illustrated so that the individual plugs and sockets may be self-aligning. In practice it may be preferred to provide this clearance between the heads of the plugs and their supporting insulation or between the heads of the sockets and their supporting insulation, or if desired both the plugs and sockets may be provided with sufficient clearance for this purpose. In practice also 50 the central pole of the electrical connection is made the ground pole. This arrangement adds considerably to the safety with which the present connection may be used inasmuch as in assembling the connection the ground connection must 55 of necessity come at the center and it becomes impossible to introduce a high tension plug into the ground socket. In addition, in practice the ground plug and its socket are made of dimensions different than the dimensions of the high 60 tension plugs and sockets, thus providing an additional safeguard against accidental connection of a high tension pole with the ground socket.

From the description thus far it will be apparent that the construction of the present plug and 65 socket connection is such as to minimize liability of current leakage from one plug or socket to the others, or of current creepage or flash over, as above described, and that the plugs and sockets are insulated in a most efficient and practical 70 75

manner both from each other and from the outer protective casings. The construction is one which lends itself particularly to use in high tension systems.

5 While the preferred embodiment of the invention has been herein illustrated and described, it will be understood that the invention may be embodied in other forms within the scope of the following claims.

10 Having thus described the invention what is claimed is:—

1. An electrical connection having, in combination, a casing provided with an insulating supporting member mounted therein, a plurality of plug members spaced apart and operatively supported by said supporting member, and elongated insulating members within which said plug members are mounted, said insulating members extending through spaced apart openings in said supporting member and projecting a substantial distance beyond the supporting member and a substantial distance beyond each end of the plug member, and a second casing arranged to telescope with the first casing and itself provided with an insulating member operatively supported therein and having a plurality of socket members adapted to cooperate with the aforesaid plug members, said socket members being mounted within elongated insulating sleeve members projecting through and operatively supported in spaced relation by the insulating supporting member in said second casing, said insulating sleeve members projecting a substantial distance beyond each side of the insulating supporting member and a substantial distance beyond each end of the socket members, said projecting insulating members forming effective barriers for current leaking across the surfaces of said insulating supporting members.
2. An electrical plug and socket connection comprising an outer casing, a plurality of plug members, a plurality of cooperative socket members, a hollow elongated insulator for each plug and socket member extended beyond the opposite ends of said plug and socket member, and means for mounting said plug and socket members and their insulators within said casing in fixed relation thereto and with each member and its insulator spaced a substantial distance from an adjacent member and its insulator and surrounded by a substantial body of air within said casing.

3. In an electrical connection, in combination, a casing, a plurality of electrical connectors, and means for operatively supporting said connectors within the casing and in insulated relation from each other and from the casing, including, a supporting disk secured to the casing in fixed relation thereto, a hollow elongated insulator for each connector extended through said supporting disk and beyond the opposite ends of the electrical connector with which it co-operates and separated on opposite sides of said disk from the hollow insulator of an adjacent electrical connector by an air space of substantial width.

4. In an electrical connection, in combination, a casing, an insulating supporting member secured within said casing, a plurality of hollow insulators extended through said supporting member and projecting beyond the front and rear surfaces thereof, electrical contact members located in said hollow insulators and having their opposite ends removed from the opposite ends of said hollow insulators a substantial distance, said hollow insulators having their projecting ends separated from one another by an air gap to cause current leaking from one contact member to an adjacent contact member to travel longitudinally of one insulator toward said insulating supporting member, across the face of the latter, and then away from said supporting member longitudinally of the adjacent insulator.

5. In an electrical connection, in combination, a casing, an insulating supporting member secured within said casing, a plurality of hollow insulators extended through said supporting member and projecting beyond one surface thereof a substantial distance and separated from each other for the length of the projecting portions by an air gap, electrical contact members located in said hollow insulators and having one end removed a substantial distance from the end of the projecting portion of the hollow insulator, said hollow insulators co-operating with the insulating supporting member to form on one side of the insulating supporting member a relatively long insulating surface over which current leaking from one contact member to an adjacent contact member is caused to pass longitudinally of one insulator toward the insulating supporting member, across the surface of the latter and then away from the latter longitudinally of the adjacent hollow insulator.
